[57] **CLAIM**

The ornamental design for a modular frozen yogurt service kiosk or similar article, as shown and described.

DESCRIPTION

FIG. 1 is a perspective view of a modular frozen yogurt service kiosk or similar article showing our new design the broken lines indicating environmental structure and forming no part of the claimed design;

FIG. 2 is a top plan view thereof;

FIG. 3 is a left side elevational view thereof;

FIG. 4 is a right side elevational view thereof; and,

FIG. 5 is a front elevational view thereof.

FIG. 1

FIG. 2

FIG. 3

FIG. 4

FIG. 5
